UNITED STATES PATENT OFFICE.

OSCAR MARSCHIETZ, OF LOUISVILLE, KENTUCKY, ASSIGNOR TO THE AIIRENS & OTT MANUFACTURING COMPANY, OF SAME PLACE.

DESIGN FOR A STANDARD FOR TRAPS AND BASINS.

SPECIFICATION forming part of Design No. 24,412, dated June 18, 1895.

Application filed May 8, 1895. Serial No. 548,604. Term of patent 7 years.

To all whom it may concern:

Be it known that I, OSCAR MARSCHIETZ, a citizen of the United States, residing at Louisville, in the county of Jefferson and State of Kentucky, have invented and produced a new and original Design for Standards for Basins and Traps, of which the following is a specification, reference being had to the accompanying drawings, showing a part thereof.

10 Figure 1 is a side elevation of a standard, showing my design. Fig. 2 is an elevation at right angles to Fig. 1, showing the edge of the standard.

The leading features of my design consist 15 of a body or center which, in side view, is of oval form, and in end view has straight parallel edges, an annular base which is connected by a short neck to the body or center, a top flange, and a short grooved neck be-

20 tween the top flange and the body or center.

A designates my newly designed standard or column. It consists of the body or center, B, the short necks, C, D, a top flange, E, and a base F.

25 In side view, the body or center is oval shaped, see Fig. 1, but in end view, the sides or edges of the body are parallel to each other. See Fig. 2. The short neck, D, at the bottom

is cylindrical and of less diameter than the horizontal diameters of the body, B, so that the surfaces of the neck, D, fall within the lines of the body or center, B. The short neck, C, is flush with and parallel to the lines of the body or center, B, and said neck, C, has an annular groove, c. The top flange, E, 35 projects horizontally from the upper edge of the neck, C. The base F, has short webs or ribs, f, which rise from the top side thereof and extend a short distance up the lower neck, D. From the lower side of the base depends 40 a central flange.

The body or center has rounding end walls, from which protrude the bosses, h, h.

On each of the sides of the oval shaped body are provided the concentric beads or 45 flanges, i, j, of which the bead, j, is within the bead, i, so as to leave the space, k.

What I claim as new is—

The design for a standard or column for basins and stands herein shown and described. 50

In testimony whereof I hereunto set my hand in the presence of two witnesses.

OSCAR MARSCHIETZ.
